CLAIM

The ornamental design for fanciful sunglasses, as shown and described.

DESCRIPTION

FIG. 1 is a front elevational view of fanciful sunglasses showing our new design;
FIG. 2 is a side elevational view thereof, the side opposite being substantially a mirror image;
FIG. 3 is a rear elevational view thereof;
FIG. 4 is a top plan view thereof;
FIG. 5 is a bottom plan view thereof; and
FIG. 6 is a perspective view thereof.
